(57) **CLAIM**

I claim the ornamental design for a candle, as shown and described.

DESCRIPTION

FIG. 1 is a front view of the candle of my new design;

FIG. 2 is a rear view thereof;

FIG. 3 is a side view thereof, shown from the right side;

FIG. 4 is a side view thereof, shown from the left side;

FIG. 5 is a top view thereof;

FIG. 6 is a bottom view thereof; and,

FIG. 7 is a perspective view thereof.

The broken-line disclosure of a base insert is for illustrative purposes only and forms no part of the claimed design.
